United States Patent Office

Des. 230,218
Patented Jan. 29, 1974

230,218

STAKE

Paul E. Freiling, 1006 Maertin, Fullerton, Calif. 92631,
and Joseph E. Smith, 606 Clarion Place, Claremont,
Calif. 91711

Filed Oct. 31, 1972, Ser. No. 302,404

Term of patent 14 years

Int. Cl. D21—04

U.S. Cl. D88—3 B

FIG. 1.

FIG. 2.

FIG. 3.

FIG. 4.

FIG. 5.

FIG. 1 is an isometric view of a stake showing our new design;

FIG. 2 is a side elevational view thereof, the opposite side being a mirror image thereto;

FIG. 3 is a rear elevational view thereof;

FIG. 4 is a top plan view thereof;

FIG. 5 is a bottom plan view thereof.

We claim:

The ornamental design for a stake, as shown and described.
